UNITED STATES PATENT OFFICE.

DELLA M. MILLER, OF TOLEDO, OHIO.

ADJUSTABLE WINDOW-SHADE BRACKET.

SPECIFICATION forming part of Letters Patent No. 634,179, dated October 3, 1899.

Application filed December 17, 1898. Serial No. 699,620. (No model.)

To all whom it may concern:

Be it known that I, DELLA M. MILLER, of Toledo, in the county of Lucas and State of Ohio, have invented a new and useful Improvement in Adjustable Window - Shade Brackets, of which the following is a specification.

It is well known that in tenant-houses having frequent changes of occupants the window-casings soon become damaged and practically ruined by reason of the numerous screw and nail holes made therein for the purpose of adjusting the ordinary window-shade brackets to accommodate the various sizes of window-shades owned by the different tenants.

The object of my invention is to overcome this difficulty by providing a simple and inexpensive window-shade bracket which can be used with shade-rollers of various lengths without changing the position of the bracket upon the window-casing, thus saving the trouble of making new screw or nail holes for each new tenant and avoiding the mutilation of the window-casing resulting therefrom. I accomplish this object by means of the device hereinafter described, and illustrated in the accompanying drawings, which are made a part hereof, and in which—

Figure 1 is a front view of a pair of my improved brackets as they appear in practical use. Fig. 2 is a front view of one of said brackets in position upon a window-casing, and Figs. 3 and 4 are side views of portions of one of said brackets detached.

1 2 are stationary brackets which are secured to the window-casing in any suitable manner, preferably by screws. In the drawings the bracket 1 is secured to the outer edge of the window-casing, (see Fig. 4;) but I do not restrict myself to this position nor to the particular form of bracket shown, any suitable stationary bracket being as well adapted to my purpose.

Between the stationary brackets 1 2 is revolvably and horizontally supported a threaded shaft 3, upon which travels a movable bracket 4. One end of the threaded shaft 3 is revolvably supported and secured against longitudinal movement in an opening in the stationary bracket 2, the other end thereof being revolvably supported in a hole through bracket

1. This hole is not screw-threaded, and the bracket 1 may be moved loosely along the shaft 3 to any desired point. The distance 55 between the two brackets 1 and 2 is thus adjustable and they may accordingly be fitted to casings of any ordinary width. The outer end of the shaft is provided with a head 5, by which it may be easily revolved by hand. 60

Supported upon the threaded shaft 3, between the stationary brackets 1 2, is a movable bracket 4, the shaft passing through a screw-threaded aperture in the bracket 4, thus providing means for moving the bracket 65 back and forth upon the shaft by turning the head 5.

The shoulder 6 (see Fig. 3) of said movable bracket 4 fits closely but movable horizontally against the vertical face of the window-casing, thus holding the bracket securely in adjusted position and making a steady rest for the end of the shade-roller.

It will be seen that I have described but one of a pair of my adjustable window-shade 75 brackets, both being substantially alike in construction, except that one of the movable brackets 4 is provided with a circular opening and the other with a vertical slot, both of the usual size and shape, for receiving the 80 axial pieces on the ends of a shade-roller. It will also be seen by referring to Fig. 1 that the positions of the two brackets upon the window-casing are reversed, the head 5 always being at the outer end. 85

Having thus described my invention, what I claim as new, and desire to secure by Letters Patent, is—

An adjustable window-shade fixture consisting of two stationary brackets, a threaded 90 shaft revolvably supported between said stationary brackets, a movable bracket supported between said stationary brackets and provided with a screw-threaded aperture through which said threaded shaft passes, 95 and a shoulder on said movable bracket fitted snugly against the window-casing, whereby said bracket may be moved back and forth by revolving the shaft.

DELLA M. MILLER.

In presence of—

WILBER A. OWEN,
L. E. BROWN.
